UNITED STATES PATENT OFFICE.

FRANK BUKACHEK AND OSCAR A. GARBUSCH, OF PINE CITY, MINNESOTA; SAID BUKACHEK ASSIGNOR TO SAID GARBUSCH.

GLASS-CUTTING BOARD.

Application filed November 14, 1921. Serial No. 515,111.

To all whom it may concern:

Be it known that we, FRANK BUKACHEK and OSCAR A. GARBUSCH, citizens of the United States, residing at Pine City, in the 5 county of Pine and State of Minnesota, have invented a new and useful Glass-Cutting Board, of which the following is a specification.

Our invention relates to glass cutting 10 boards, and the object is to provide a convenient, efficient and otherwise improved board upon which to readily measure, cut and separate the cut parts of glass of any thickness used for window lights, picture 15 frames, etc.

In the accompanying drawing:

Fig. 1 is a top or plan view of our improved glass board with a piece of glass placed upon it in position to be cut.

20 Fig. 2 is a right hand edge view of Fig. 1.

Fig. 3 is a lower edge view of Fig. 1.

Referring to the drawing by reference numerals, 1 designates the board proper. It is reinforced and stiffened by cleats 2 se- 25 cured to its under side, and in the upper side it is provided with a groove 3 serving as a clearance for the fingers of the operator when he desires to pick up the glass from the board.

30 Parallel to said groove is secured upon one edge of the board a glass measuring and guiding scale bar 4, and at right angle to said bar and about half an inch from it is a heavier bar 5, which has its outer edge 6 spaced about one eighth of an inch inward 35 from the edge 7 of the board, and its inner edge beveled at 8 and provided with a scale of inches and fractions of inches starting at the point 9 and extending with increased

40 numbers to any desired length according to the size of the board. This scale bar 5 is slidable up and down on studs 10 fixed in the board. The space 11 between the two scale bars is a clearance for the glass cutter to 45 pass through in cutting the glass. The scale of inches and fractions of inches on the bar 4 does not start at the point 12 but at a point 13, that is, at the crease which an ordinary glass cutter drawn along the inner

edge of bar 5 cuts about one-sixteenth of an 50 inch from said edge of the bar.

In the operation or use of the board, the glass is placed as 15 upon the board and guided by the scale bar 4 is pushed outward underneath the bar 5, the latter being at the 55 time sufficiently raised for the purpose. When the previously squared corner 16 of the glass reaches the desired number or mark on bar 4, the operator presses downward on the bar 5 while drawing the cutter 60 along the edge 5^a of the bar and after the score 14 is thus produced in the glass the latter is pushed outward until the score ap- 65 pears close outside the edge 6 of the bar, the portion 15^x of the glass is then forced down- 65 ward by one hand and broken at the score while the other hand is resting on the bar 5 to prevent tipping of the main body of the glass. If the glass is further to be cut, say 70 at the line 17 it is turned and pushed with 70 said line to the position of the score 14 and is there cut in the manner already described, whereupon the ready cut piece 15 is picked up and removed. Such picking up, turning 75 and removing of the glass is greatly facilitated by the groove 3 which admits the operator's fingers to get under the glass to pick it up quickly and also to put it down without dropping it.

It will be understood that we consider 80 the slight projecting 18 of the board beyond the edge 6 of the bar 5 as a valuable feature since experimenting has demonstrated that said feature causes the glass to break with much more square and smooth edges than 85 when the portion 15^x is all unsupported be- 75 yond the face 6 of the bar 5 holding the glass.

What we claim is:

1. A glass cutting board having one edge 90 near which to break the glass after it has been scored by the cutting tool, vertical posts fixed in the board near said edge, and a main scale bar having apertures making it 95 slidable up and down on the posts, said edge of the board projecting a short distance outward beyond said scale bar.

2. The structure specified in claim 1, and

- a second scale bar fixed upon the board at right angles to the main scale bar, said second bar having its scale increased from the end nearest the first bar and arranged as starting a short distance from the main bar, said bars being spaced apart as a clearance for the cutting tool which is guided by the inner edge of the main scale bar.
- 3. The structure specified in claim 2, said board having in its top a groove formed in parallel relation to the fixed side bar.

In testimony whereof we affix our signatures.

FRANK BUKACHEK.
OSCAR A. GARBUSH.
